GAS BLAST CIRCUIT BREAKER

André Latour, Grenoble, France

Application October 1, 1951, Serial No. 249,044
In France April 6, 1940Section 1, Public Law 690, August 8, 1946
Patent expires April 6, 1960

15 Claims. (Cl. 200—148)

1

The present invention relates to a gas blast circuit breaker.

The present application is a continuation-in-part of Patent No. 2,574,334, dated November 6, 1951, which matured from the copending application, Ser. No. 763,024, filed July 23, 1947, for "Air Blast Circuit Breakers," and of application Ser. No. 723,726, now Patent No. 2,584,888, dated February 5, 1952.

It is an object of the present invention to provide a structure which renders the gas blast circuit breaker particularly suitable for interrupting currents having a high voltage.

It is another object of the present invention to provide an arrangement which has a reduced overall height.

It is a further object of the present invention to render all parts and more particularly the contacts of the gas blast circuit breaker easily accessible.

The present invention comprises in its broadest aspect a housing forming a chamber therein, two contact members having end portions, respectively, facing each other, the contact members being arranged in the chamber movably from a first position into a second position, the facing end portions of the contact members being in the second position thereof farther from each other than in the first position, means for establishing an electrical connection between the facing end portions of the contact members while the same are in the first position thereof, the contact members being electrically disconnected when in the second position thereof, means for introducing gas under pressure into the chamber, and means operated by the gas under pressure when the pressure of the gas reaches a predetermined level, the gas-operated means moving the contact members simultaneously from the first into the second position thereof, whereby the gas under pressure enters the gap created by the movement of the contact members between the end portions thereof and extinguishes the arc formed therebetween.

Preferably a gas blast circuit breaker according to the invention comprises enclosure means enclosing the facing end portions of the contact members while the same are in the first position and while they move from the first position into the second position so as to prevent access of gas under pressure thereto.

A preferred embodiment of the present invention comprises a housing forming two preferably horizontal chambers therein arranged coaxially to each other and symmetrically with respect to

2

a median plane which is preferably vertical, and the means for introducing the gas under pressure include conduit means having an axis of symmetry arranged in the median plane of the two chambers, the conduit means communicating with the two chambers and introducing gas under pressure into the chambers.

Preferably two current terminals are connected, respectively, to the two movable contacts, one of the terminals leading current into the circuit breaker, the other of the terminals leading current out of the circuit breaker.

In one embodiment of the present invention the circuit breaker comprises two stationary nozzle members arranged at opposite sides of the hollow member and extending, respectively, into the two horizontal chambers, the two movable contacts cooperating, respectively, in the first position thereof with the stationary nozzle members.

20 In another embodiment of the present invention two stationary contact members are arranged at the opposite sides of the hollow member and extend, respectively, into the two horizontal chambers, means being provided for establishing an electrical connection between the stationary contact members so as to connect the movable contact members electrically with each other in the first position thereof.

30 The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings, in which:

Fig. 1 is a sectional elevation of a gas blast breaker according to the present invention;

40 Fig. 2 is a cross-section along the line x_1-x_2 of Fig. 1;

Fig. 3 shows a modified detail of the device shown in Fig. 1;

Fig. 4 shows the same detail in another modification; and

Fig. 5 is a diagram showing the circuit breaker according to Fig. 1 together with auxiliary control elements for the gas blast.

Referring now to the drawings, and first to Figs. 1 and 2, the circuit breaker comprises two equal chambers $100, 100'$ which are symmetrically and coaxially arranged with respect to a median plane 101 indicated by a broken line. The chambers $100, 100'$ comprise, respectively, hollow insulators 30 and $30'$ and metal hoods 27 and $27'$

arranged at the ends of the hollow insulators which face in opposite directions.

Each chamber encloses a contact arrangement which will be described hereinafter for the chamber 100 only. It should be understood that the chamber 100' encloses an equal arrangement.

The hollow insulators 30 and 30' are screwed with the ends arranged oppositely to each other to a substantially annular and hollow member 31 which is supported by a hollow vertical insulator 33 forming part of a conduit 102 carrying the compressed gas or air to the circuit breaker. The hollow insulator 33 and the hollow member 31 are arranged symmetrical to the median plane 101 and communicate with each other.

The hollow member 31 has the shape more clearly seen from Figs. 1 and 2 and consists of a foot portion 104 screwed to the vertical insulator 33 and connected to a hollow cylindrical portion 105 provided with opposite apertures such as 106 communicating with the interior of the hollow insulators 30 and 30'. Furthermore, the hollow member 31 comprises a header portion 107 extending from the top thereof downward to a curved portion 108 provided with opposite apertures for the accommodation of two hollow horizontal stationary members 1, 1' being designed as nozzles made of insulating material into which extend two movable hollow contact members 2, 2' in circuit-closing position thereof, referred hereinafter as the first position.

The upper part of the hollow member 31 is shaped as a chamber 4, hereinafter called the exhaust chamber, communicating with a horizontal duct 9 having a plane of symmetry coinciding with the median plane 101 and leading to two opposite vertical side branches 3 and 3' (Fig. 2) which have openings 10, 10', respectively, at the bottom thereof which are separated from the interior of the branches 3, 3' by cylinders 8, 8', respectively, consisting of one or more layers of metal gauze for cooling the gas or air blast leaving the circuit breaker in the manner more fully described hereinafter.

The exhaust chamber 4 is connected to the duct 9 by an orifice 5 which can be more or less completely shut by a valve 6 acted upon by a compression spring 7 so that the valve 6 is in open position unless an overpressure prevails in the exhaust chamber.

The hood 27 is provided with an exhaust opening 26 and a terminal 110 whereas the hood 27' is provided with an exhaust opening 26' and a terminal 111 forming part of a disconnecting switch 13 connected in series with the circuit breaker (see also Fig. 5).

The movement of the movable contact member 2 shown in open position in dotted lines is controlled by a movable piston 14 arranged in a cylinder 15 coaxially arranged within the hollow insulator 30. The movable contact member 2 is held in the first position thereof by a compression spring 16 inserted between the piston 14 and a stationary guiding member 15'. The right hand face of the piston 14 may be subjected to the pressure of compressed gas through one or more apertures 17 provided in the wall of the cylinder 15. The left hand face of the piston 14 may be subjected at will either to atmospheric pressure or to the pressure of the compressed gas by a duct 18 connecting the interior of the cylinder 15 with a distributor 19 having two positions more fully to be described hereinafter and being connected to the interior of the chamber 100 by an opening 35.

The central hollow duct of the movable contact member 2 communicates with the atmosphere by an orifice 21 provided in the rear part of the guiding member 15'. The orifice 21 may be closed by a valve 22 kept in open position by a spring 23. Furthermore the hollow duct of the movable contact member 2 is connected to the atmosphere by one or more lateral orifices 24 in the guiding member 15', which are closed by the movable contact member 2 during the opening movement thereof.

Both groups of orifices 24 and 21 open into an exhaust chamber 25' enclosed in a wire mesh 25 and protected from weather influences by the hood 27. The left end of cylinder 15 is designed as a flange 28 attached to the insulator 30 by a collar 29.

The distributor 19 is controlled by an insulating pusher 38 actuated by a cam 39 integral with an insulating rod 40 which is rotated by a crank 41 actuated by a connecting rod 42 controlled by a piston 43, which is moved pneumatically against the force of a spring 45.

When the breaker is closed the movable contact members abut against each other with the facing end portions thereof. In this position no air or gas flows can occur, in the chamber 4 or within the duct of the movable contact members such as 2, whatever the pressure in the interior of the insulators 30, 30' and 33 may be. If it is intended to open the circuit breaker a gas such as air under pressure is admitted through the conduit 102 to the chambers 100 and 100' so that the right hand face of the piston 14 is subjected to the pressure of the gas passing through the apertures 17 and the lefthand face to atmospheric pressure transmitted by the duct 18, the distributor 19 being in this moment in the position shown on Fig. 1. Thus the piston 14 moves outwardly, compresses the spring 16, and drives the movable contact member 2 into the second position thereof indicated by dotted lines in which it closes the orifice 24.

In the second position of the movable contact member 2, the compressed gas flows rapidly through the stationary nozzles 1, 1' the exhaust chamber 4, the orifice 5, the duct 9 and through the openings 10 and 10'. Furthermore compressed gas flows through the hollow of the movable contact member 2, the orifice 21 and the exhaust opening 26 of the hood 27. Thus a very strong blast is produced and the arc formed between the movable contact members is rapidly extinguished. As soon as the gas blast becomes effective, the valves 6 and 22 begin to close but owing to their mass, cannot complete the closing strokes thereof before the lapse of a certain time, exceeding the maximum time period necessary for extinguishing the arc.

When the valves 22 and 6 are closed, the gas blast is interrupted, however the gas pressure is maintained without appreciable loss within the insulators 30, 30' until the circuit is finally interrupted, thus maintaining the insulation between the contacts.

The final opening of the circuit is secured by the opening of the disconnecting switch 13.

If the disconnecting switch 13 is left in closed position and a closing of the circuit is intended, the distributor 19 is actuated by subjecting the piston 43 to a pressure which drives the same against the force of the spring 45 and rotates crank 41, the rod 40 and the arm 39, thus actuating the pusher 38 so as to bring the distributor 19 into a position in which the valve 36 thereof

establishes a connection between the duct 18 and the opening 35 communicating with the interior of chamber 160. In consequence thereof, the piston 14 is subjected on both faces to the same pressure and is rapidly moved by the force of the spring 16, thus moving the movable electrode 2 from the second outer position to the first position thereof which closes the circuit breaker. The flow of compressed gas into the chamber 4 is closed and the apertures 24 are opened through which the residual compressed gas is exhausted immediately into the open air. The valves 6 and 22 are no longer exposed to any pressure and are returned to the open position by their respective springs.

The device is then ready for a new operation.

It should be noted that during the closing movement a very short blast occurs, as soon as the movable contact members such as 2 uncover the apertures 24. This is advantageous because the ionized gases formed by the closing arc are removed so that a subsequent break is not disturbed by the pressure of ionized gases.

It should be noted that in the embodiment shown in Fig. 1 the closing of the breaker is achieved by putting the two movable contact members 2 in direct contact with the end faces thereof contacting each other. The reduction of pressure in the chamber 4 begins as soon as the movable contact members enter the neck of the nozzles such as 1 and proceeds at a very fast rate so as to be achieved at the moment when the contact members meet. If necessary, grooves may be provided on the contacting faces of the movable contact members.

In the embodiment shown in Fig. 3 the insulating nozzles 1 are designed as hollow stationary contact members 120, 121 which cooperate with the movable contact members 2, 2', respectively. The stationary contact members 120 and 121 are electrically connected by an electrical connection which may be formed by the rounded portion 108 of the header portion 107 of the hollow member 31. Of course, at least the header portion 107 should consist of metal in this case. However, if desired, a separate member (not shown) may be provided for electrically connecting the stationary contact members 120, 121.

In the embodiment shown in Fig. 4, the stationary contact members 120, 121 consist of one piece and include a connecting element 122.

In Fig. 5 a device according to the invention is shown together with the accessories thereof. The circuit breaker is denoted by 47. The disconnecting switch 13 is shown in closed position. 48 is a current transformer feeding a tripping relay 50. The breaker 47 is supplied with compressed gas from a reservoir 51 through a pneumatic valve 52, controlled by an electro-valve 53. A branch pipe 54 starting at the valve 52 supplies through a duct 55 a device securing a rapid reclosing of the breaker without intervening of the disconnecting switch and through a duct 56 the pneumatic control of the disconnecting switch. A cock 57 provided in the duct 55 and actuated manually or mechanically allows to render, if desired, the reclosing device inoperative. 58 and 59 are pneumatic valves having their opening timed by calibrated throttles 60 and 61, respectively, the cross-sections of which are calculated as functions of the dead space of the cylinders controlling said valves, so that the pressure necessary to actuate these valves is only reached after a predetermined lapse of time. The dead space situated behind the piston of

the valve 58 may be brought to atmospheric pressure by a discharge valve 62 which opens when a certain pressure exists in a duct 63.

5 A valve 64 closes by the actuation thereof a supply duct 65 for compressed air and connects the ducts 63 and 65 to atmospheric pressure. The valve 64 is an electro-valve closing the gas supply when its electro-magnet is energized and is maintained energized by the contact 67 thereof.

10 68 is a manometric device closing a contact 69 when the pressure has become sufficiently strong in the duct 66.

A similar device 70 opens a contact 71, when actuated by the pressure prevailing in a chamber 73, pressure being transmitted to the chamber 73 with a delay by a throttle 72. The piston

15 43, as has been explained in connection with Fig. 2, controls, when moving in the direction of the arrow RE, the rapid reclosing and when moving 20 in the direction of the arrow D the release of the breaker.

The movement of the disconnecting switch 13 is controlled by a piston 74 sliding in a cylinder 75. The opening of the disconnecting switch 13 is accomplished by supplying compressed gas to 25 one face of the piston 74 through the valve 58 and a duct 76, and its closing by supplying the compressed gas to the other face of the piston 74 through a closing valve or an electro-valve 30 (not shown). At the end of its opening stroke, this device opens an auxiliary contact 77 and at the end of its closing stroke an auxiliary contact 78, thus bringing the closing valve (not shown) into rest position. An auxiliary source 79 supplies 35 low voltage current to the different circuits of the arrangement.

The breaker may be utilized as ordinary circuit-breaker or as a circuit-breaker with rapid reclosure.

40 In the first case, the cock 57 is closed, the operation being as follows:

When an excess current occurs on the line 43, the current transformer 48 energizes the relay 50, which closes the contact 81, which in turn actuates the electro-valve 53, which opens the main valve 52. The contact 82 closes at the same time, but remains inoperative because of the contact 69 which is open. The circuit breaker 47 is set under pressure, the contacts part rapidly, the arc 45 is extinguished, the open contacts close the exhaust orifices, as more fully explained hereinabove. Thus the current on the line 43 is interrupted and the relay 50 opens at once its contacts. The electrovalve 53 remains nevertheless 50 open, because the magnet coil thereof is still energized by current flowing through the maintaining contact 80. After a certain time, however, predetermined by the retarding throttle 60, the valve 58 opens and actuates the disconnecting 55 switch 13 which toward the end of its stroke opens the contact 71 and cuts the supply of the electro-valve 53 so that the latter closes, thus causing the closing of the main valve 52 and connecting the circuit-breaker 47 and all ducts to atmospheric pressure. Hereupon the contacts of the 60 circuit breaker close which involves no inconvenience as the disconnecting switch 13 is still open.

65 In the second case, when the rapid reclosing device is to be used the cock 57 remains open and the operation is the same as in the first case up to the moment when the contacts of the breaker 47 part. But as the retardation of the throttle 61 is shorter than the retardation of the throttle 60, the valve 59 opens before the opening of valve

58 and supplies pressure to the ducts 63 and 66. The pneumatic valve 59 puts through the duct 63 the control chamber of the valve 62 under pressure and prevents it from opening as long as the pressure has not disappeared in the duct 63. The compressed gas flowing through the pipe 65 drives the piston 43 in the direction of the arrow RE and, through rotation of the rod 40, causes the closing of the contacts of the circuit-breaker 47, in a fully compressed gas atmosphere, as has been explained hereinabove in connection with Fig. 2. The effect of this closure is, as already mentioned, the rapid opening of the valves 6 and 22 (Fig. 2) thus allowing for a subsequent new blast.

If the fault on the line 48 has disappeared, the closing of the contacts of the breaker is not followed by any abnormal current and the relay 50 keeps its own contact open. After a certain time, determined by the throttle 72 feeding the volumetric chamber 73, the manometric device 79 opens the contact 71. Hereby the electro-valve 53 and the valve 52 are closed and the arrangement returns to the initial position without any actuation of the disconnecting switch 13.

If, however, the fault in the line persists, the closing of the contacts of the breaker restores the abnormal current, which then actuates the relay 50 once more.

Thus the relay 50 closes its contacts 81 and 82. The closing of contact 81 has no consequence, the electro-valve being already fed with current by its own contact 80, because the contact 69 is closed as soon as the duct 66 is under pressure. Thus the electro-valve 64 opens and stays open owing to the current supplied by contact 61. The valve 64 shuts off the supply 65 of compressed gas and connects the ducts 63 and 66 to atmospheric pressure. This causes a backward stroke of the piston 43 in the direction of the arrow D and a new trip of the breaker 47 which by the opening of the contacts thereof interrupts the short circuit a second time.

Furthermore the pneumatic valve 62 closes, thus permitting the valve 58 to open after a time predetermined by the throttle 60. The opening of the valve 58 causes the opening of the disconnecting switch 13 which at the end of its strokes opens the contact 77 and puts the electro-valves 54 and 53 out of action. In this way the whole arrangement returns to the initial position thereof. If the line 48 is to be closed again pressure is brought to bear by means of a device not shown in the drawings, for instance an electro-valve, on that face of the piston 74 which corresponds to the closing. The contact 77 is reclosed and the breaker is ready for a new trip.

It will be understood that each of the elements described above, or two or more together, may also find a useful application in other types of gas blast circuit breakers differing from the types described above.

While the invention has been illustrated and described as embodied in a gas blast circuit breaker having two horizontal chambers, it is not intended to be limited to the details shown, since various modifications and structural changes may be made without departing in any way from the spirit of the present invention.

Without further analysis, the foregoing will so fully reveal the gist of the present invention that others can by applying current knowledge readily adapt it for various applications without omitting features that, from the standpoint of prior art, fairly constitute essential characteristics of the generic or specific aspects of this invention and,

therefore, such adaptations should and are intended to be comprehended within the meaning and range of equivalence of the following claims.

What is claimed as new and desired to be secured by Letters Patent is:

1. In a gas blast circuit breaker, in combination, a housing forming two horizontal chambers therein arranged coaxially to each other and symmetrically with respect to a vertical plane and an exhaust chamber located between said two chambers, said housing including wall means separating said exhaust chamber from said two chambers and being formed with oppositely arranged openings for communication between said exhaust chamber and said two chambers; outlet means communicating with said exhaust chamber; two contact members having end portions, respectively, facing each other, said contact members being arranged, respectively, in said chambers movably from a first position into a second position in which said contact members pass through said openings, and said end portions thereof are located in said exhaust chamber, said facing end portions of said contact members being in the second position thereof farther from each other than in the first position and located in said two chambers; means for establishing an electrical connection between said facing end portions of said contact members while the same are in the first position thereof, said contact members being electrically disconnected when in the second position thereof; conduit means having an axis of symmetry arranged in the vertical plane of said two chambers, said conduit means communicating with said two chambers and introducing gas under pressure into said chambers; and means operated by the gas under pressure when the pressure of the gas reaches a predetermined level, said gas-operated means moving said contact members simultaneously from the first into the second position thereof, whereby the gas under pressure enters said exhaust chamber through said openings and thereupon the gap created by the movement of said contact members between said end portions thereof and extinguishes the arc formed therebetween mainly passing through said outlet means.
2. A gas blast circuit breaker, comprising in combination, a housing forming two chambers and an exhaust chamber located between said two chambers, said housing including wall means separating said exhaust chamber from said two chambers and being formed with oppositely arranged openings for communication between said exhaust chamber and said two chambers; outlet means communicating with said exhaust chambers; two contact members having end portions, respectively, facing each other, said contact members being arranged, respectively, in said chambers movably from a first position in which said contact members pass through said openings, and said end portions thereof are located in said exhaust chamber into a second position, said facing end portions of said contact members being in contact with each other in the first position of said contact members and in the second position thereof being farther from each other than in the first position and located in said two chambers, so as to establish an electrical connection between said facing end portions of said contact members while the same are in the first position thereof, said contact members being electrically disconnected when in the second position thereof; means for introducing gas under pressure into said chambers; and means operated by the gas

under pressure when the pressure of the gas reaches a predetermined level, said gas-operated means moving said contact members simultaneously from the first into the second position thereof, whereby the gas under pressure enters said exhaust chamber through said openings and thereupon the gap created by the movement of said contact members between said end positions thereof and extinguishes the arc formed therebetween mainly passing through said outlet means.

3. In a gas blast circuit breaker, in combination, a housing forming two horizontal chambers therein arranged coaxially to each other and symmetrically with respect to a vertical plane and an exhaust chamber located between said two chambers, said housing including wall means separating said exhaust chamber from said two chambers and being formed with oppositely arranged openings for communication between said exhaust chamber and said two chambers; outlet means communicating with said exhaust chamber; two contact members having end portions, respectively, facing each other, said contact members being arranged, respectively, in said chambers movably from a first position into a second position in which said contact members pass through said openings, and said end portions thereof are located in said exhaust chamber, said facing end portions of said contact members being in contact with each other in the first position of said contact members and in the second position thereof being farther from each other than in the first position and located in said two chambers, so as to establish an electrical connection between said facing end portions of said contact members while the same are in the first position thereof, said contact members being electrically disconnected when in the second position thereof; means for introducing gas under pressure into said chambers; and means operated by the gas under pressure when the pressure of the gas reaches a predetermined level, said gas-operated means moving said contact members simultaneously from the first into the second position thereof, whereby the gas under pressure enters said exhaust chamber through said openings and thereupon the gap created by the movement of said contact members between said end positions thereof and extinguishes the arc formed therebetween mainly passing through said outlet means.

4. A gas blast circuit breaker, comprising in combination, a housing forming two chambers therein arranged coaxially to each other and symmetrically with respect to a median plane and an exhaust chamber located between said two chambers, said housing including wall means separating said exhaust chamber from said two chambers and being formed with oppositely arranged openings for communication between said exhaust chamber and said two chambers; outlet means communicating with said exhaust chamber; two stationary contact members arranged in said chambers, respectively, symmetrically and close to the median plane, and passing through said openings; two contact members arranged, respectively, in said chambers movably from a first position into a second position, said movable contact members having end portions cooperating, respectively, in the first position thereof with said stationary contact members and being located in said exhaust chamber, and being farther from each other in the second position thereof than in the first position and located in said two

chambers; an electrical connection between said stationary contact members; conduit means having an axis of symmetry arranged in the median plane of said two chambers, said conduit means communicating with said two chambers and introducing gas under pressure into said chambers; and means operated by the gas under pressure when the pressure of the gas reaches a predetermined level, said gas-operated means moving said movable contact members simultaneously from the first into the second position thereof, whereby the gas under pressure enters said exhaust chamber through said openings and thereupon the gap created by the movement of said movable contact members between said end portions thereof and extinguishes the arc formed therebetween mainly passing through said outlet means.

5. A gas blast circuit breaker, comprising in combination, a housing forming two horizontal chambers therein arranged coaxially to each other and symmetrically with respect to a vertical plane and an exhaust chamber located between said two chambers, said housing including wall means separating said exhaust chamber from said two chambers and being formed with oppositely arranged openings for communication between said exhaust chamber and said two chambers; outlet means communicating with said exhaust chamber; two stationary contact members arranged in said chambers, respectively, symmetrically and close to the vertical plane, and passing through said openings; two contact members arranged, respectively, in said chambers movably from a first position into a second position, said movable contact members having end portions cooperating, respectively, in the first position thereof with said stationary contact members and being located in said exhaust chamber, and being farther from each other in the second position thereof than in the first position and located in said two chambers; an electrical connection between said stationary contact members; conduit means having an axis of symmetry arranged in the vertical plane of said two chambers, said conduit means communicating with said two chambers and introducing gas under pressure into said chambers; and means operated by the gas under pressure when the pressure of the gas reaches a predetermined level, said gas-operated means moving said movable contact members simultaneously from the first into the second position thereof, whereby the gas under pressure enters said exhaust chamber through said openings and mainly passing the gap created by the movement of said movable contact members between said end portions thereof and extinguishes the arc formed therebetween thereupon through said outlet means.

6. A gas blast circuit breaker, comprising in combination, a housing forming two chambers therein arranged coaxially to each other and symmetrically with respect to a median plane and an exhaust chamber located between said two chambers, said housing including wall means separating said exhaust chamber from said two chambers and being formed with oppositely arranged openings for communication between said exhaust chamber and said two chambers; outlet means communicating with said exhaust chamber; two stationary contact members arranged in said chambers, respectively, symmetrically and close to the median plane, and passing through said openings; two contact members arranged, respectively, in said chambers movably from a first position into a second position, said movable

11

contact members having end portions cooperating, respectively, in the first position thereof with said stationary contact members and being located in said exhaust chamber, and being farther from each other in the second position thereof than in the first position and located in said two chambers; two current terminals connected, respectively, to said two movable contacts, one of said terminals leading current into the circuit breaker, the other of said terminals leading the current out of the circuit breaker; an electrical connection between said stationary contact members; conduit means having an axis of symmetry arranged in the median plane of said two chambers, said conduit means communicating with said two chambers and introducing gas under pressure into said chambers; and means operated by the gas under pressure when the pressure of the gas reaches a predetermined level, said gas-operated means moving said movable contact members simultaneously from the first into the second position thereof, whereby the gas under pressure enters said exhaust chamber through said openings and mainly passing the gap created by the movement of said movable contact members between said end portions thereof and extinguishes the arc formed therebetween thereupon through said outlet means.

7. A gas blast circuit breaker, comprising in combination, a housing forming two horizontal chambers therein arranged coaxially to each other and symmetrically with respect to a vertical plane and an exhaust chamber located between said two chambers, said housing including wall means separating said exhaust chamber from said two chambers and being formed with oppositely arranged openings for communication between said exhaust chamber and said two chambers; outlet means communicating with said exhaust chamber; two stationary contact members arranged in said chambers, respectively, symmetrically and close to the vertical plane, and passing through said openings; two contact members arranged, respectively, in said chambers movably from a first position into a second position, said movable contact members having end portions cooperating, respectively, in the first position thereof with said stationary contact members and being located in said exhaust chamber, and being farther from each other in the second position thereof than in the first position and located in said two chambers; two current terminals connected, respectively, to said two movable contacts, one of said terminals leading current into the circuit breaker, the other of said terminals leading the current out of the circuit breaker; an electrical connection between said stationary contact members; conduit means having an axis of symmetry arranged in the vertical plane of said two chambers, said conduit means communicating with said two chamber and introducing gas under pressure into said chambers; and means operated by the gas under pressure when the pressure of the gas reaches a predetermined level, said gas-operated means moving said movable contact members simultaneously from the first into the second position thereof, whereby the gas under pressure enters said exhaust chamber through said openings and mainly passing the gap created by the movement of said movable contact members between said end portions thereof and extinguishes the arc formed therebetween thereupon through said outlet means.

3. A gas blast circuit breaker, comprising in combination, a housing forming two chambers

12

therein arranged coaxially to each other and symmetrically with respect to a median plane and an exhaust chamber located between said two chambers, said housing including wall means separating said exhaust chamber from said two chambers and being formed with oppositely arranged openings for communication between said exhaust chamber and said two chambers; outlet means communicating with said exhaust chamber; two stationary contact members arranged in said chambers, respectively, symmetrically and close to the median plane, and passing through said openings, said two stationary contact members consisting of one piece; two contact members arranged, respectively, in said chambers movably from a first position into a second position, said movable contact members having end portions cooperating, respectively, in the first position thereof with said stationary contact members and being located in said exhaust chamber, and being farther from each other in the second position thereof than in the first position and located in said two chambers; an electrical connection between said stationary contact members; conduit means having an axis of symmetry arranged in the median plane of said two chambers, said conduit means communicating with said two chambers and introducing gas under pressure into said chambers; and means operated by the gas under pressure when the pressure of the gas reaches a predetermined level, said gas-operated means moving said movable contact members simultaneously from the first into the second position thereof, whereby the gas under pressure enters said exhaust chamber through said openings and thereupon the gap created by the movement of said movable contact members between said end portions thereof and extinguishes the arc formed therebetween mainly passing through said outlet means.

9. A gas blast circuit breaker, comprising in combination, a housing forming two horizontal chambers therein arranged coaxially to each other and symmetrically with respect to a vertical plane and an exhaust chamber located between said two chambers, said housing including wall means separating said exhaust chamber from said two chambers and being formed with oppositely arranged openings for communication between said exhaust chamber and said two chambers; outlet means communicating with said exhaust chamber; two stationary contact members arranged in said chambers, respectively, symmetrically and close to the vertical plane, and passing through said openings, said two stationary contact members consisting of one piece; two contact members arranged, respectively, in said chambers movably from a first position into a second position, said movable contact members having end portions cooperating, respectively, in the first position thereof with said stationary contact members and being located in said exhaust chamber and being farther from each other in the second position thereof than in the first position and located in said two chambers; an electrical connection between said stationary contact members; conduit means having an axis of symmetry arranged in the vertical plane of said two chambers, said conduit means communicating with said two chambers and introducing gas under pressure into said chambers; and means operated by the gas under pressure when the pressure of the gas reaches a predetermined level, said gas-operated means moving said movable contact members simultaneously from the first into the second position thereof, whereby the gas under pressure enters said exhaust chamber through said openings and thereupon the gap created by the movement of said movable contact members between said end portions thereof and extinguishes the arc formed therebetween mainly passing through said outlet means.

second position thereof, whereby the gas under pressure enters said exhaust chamber through said openings and thereupon the gap created by the movement of said movable contact members between said end portions thereof and extinguishes the arc formed therebetween mainly passing through said outlet means.

10. A gas blast circuit breaker, comprising in combination, a housing forming two chambers therein arranged coaxially to each other and symmetrically with respect to a median plane and an exhaust chamber located between said two chambers, said housing including wall means separating said exhaust chamber from said two chambers and being formed with oppositely arranged openings for communication between said exhaust chamber and said two chambers; outlet means communicating with said exhaust chamber; two stationary contact members arranged in said chambers, respectively, symmetrically and close to the median plane, and passing through said openings, said two stationary contact members consisting of one piece; two contact members arranged, respectively, in said chambers movably from a first position into a second position, said movable contact members having end portions cooperating, respectively, in the first position thereof with said stationary contact members and being located in said exhaust chamber, and being farther from each other in the second position thereof than in the first position and located in said two chambers; two current terminals connected, respectively, to said two movable contacts, one of said terminals leading current into the circuit breaker, the other of said terminals leading the current out of the circuit breaker; an electrical connection between said stationary contact members; conduit means having an axis of symmetry arranged in the median plane of said two chambers, said conduit means communicating with said two chambers and introducing gas under pressure into said chambers; and means operated by the gas under pressure when the pressure of the gas reaches a predetermined level, said gas-operated means moving said movable contact members simultaneously from the first into the second position thereof, whereby the gas under pressure enters said exhaust chamber through said openings and thereupon the gap created by the movement of said movable contact members between said end portions thereof and extinguishes the arc formed therebetween mainly passing through said outlet means.

11. A gas blast circuit breaker, comprising in combination, a housing forming two horizontal chambers therein arranged coaxially to each other and symmetrically with respect to a vertical plane and an exhaust chamber located between said two chambers, said housing including wall means separating said exhaust chamber from said two chambers and being formed with oppositely arranged openings for communication between said exhaust chamber and said two chambers; outlet means communicating with said exhaust chamber; two stationary contact members arranged in said chambers, respectively, symmetrically and close to the vertical plane, and passing through said openings, said two stationary contact members consisting of one piece; two contact members arranged, respectively, in said chambers movably from a first position into a second position, said movable contact members having end portions cooperating, respectively, in the first position thereof with said stationary contact

members and being located in said exhaust chamber, and being farther from each other in the second position thereof than in the first position and located in said two chambers; two current terminals connected, respectively, to said two movable contacts, one of said terminals leading current into the circuit breaker, the other of said terminals leading the current out of the circuit breaker; an electrical connection between said stationary contact members; conduit means having an axis of symmetry arranged in the vertical plane of said two chambers, said conduit means communicating with said two chambers and introducing gas under pressure into said chambers; and means operated by the gas under pressure when the pressure of the gas reaches a predetermined level, said gas-operated means moving said movable contact members simultaneously from the first into the second position thereof, whereby the gas under pressure enters said exhaust chamber through said openings and thereupon the gap created by the movement of said movable contact members between said end portions thereof and extinguishes the arc formed therebetween mainly passing through said outlet means.

12. A gas blast circuit breaker, comprising in combination, a hollow vertical support; a hollow member arranged on said hollow vertical support and having an exhaust chamber communicating therewith; two hollow horizontal insulators arranged on opposite sides of said hollow member so as to communicate with said exhaust chamber, said two hollow horizontal insulators forming two horizontal chambers arranged coaxially to each other and symmetrical with respect to said hollow member; two stationary nozzle members arranged at the opposite sides of said hollow member and extending, respectively, into said two horizontal chambers and into said exhaust chamber; two contact members arranged, respectively, in said chambers movably from a first position into a second position, said movable contact members cooperating, respectively, in the first position thereof with said stationary nozzle members and being farther from each other in the second position thereof than in the first position and located in said two chambers; means for establishing an electrical connection between said movable contact members in the first position thereof, said movable contact members being electrically disconnected when in the second position thereof; means including said hollow vertical support for introducing gas under pressure into said chambers; and means operated by the gas under pressure when the pressure of the gas reaches a predetermined level, said gas-operated means moving said movable contact members simultaneously from the first into the second position thereof, whereby the gas under pressure enters said exhaust chamber and the gap created by the movement of said contact members and extinguishes the arc formed therebetween.

13. A gas blast circuit breaker, comprising in combination, a hollow vertical support; a hollow member arranged on said hollow vertical support and having an exhaust chamber communicating therewith; two hollow horizontal insulators arranged on opposite sides of said hollow member so as to communicate with said exhaust chamber, said two hollow horizontal insulators forming two horizontal chambers arranged coaxially to each other and symmetrical with respect to said hollow member; two stationary contact members arranged at the opposite sides of said

hollow member and extending, respectively, into said two horizontal chambers and into said exhaust chamber; two contact members arranged, respectively, in said chambers movably from a first position into a second position, said movable contact members cooperating, respectively, in the first position thereof with said stationary contact members and being farther from each other in the second position thereof than in the first position and located in said two chambers; means for establishing an electrical connection between said stationary contact members so as to connect said movable contact members electrically with each other in the first position thereof, said movable contact members being electrically disconnected when in the second position thereof; means including said hollow vertical support for introducing gas under pressure into said chambers; and means operated by the gas under pressure when the pressure of the gas reaches a predetermined level, said gas operated means moving said movable contact members simultaneously from the first into the second position thereof, whereby the gas under pressure enters said exhaust chamber and the gap created by the movement of said contact members and extinguishes the arc formed therebetween.

14. A gas blast circuit breaker, comprising in combination, a hollow vertical support; a hollow member arranged on said hollow vertical support and having an exhaust chamber communicating therewith; two hollow horizontal insulators arranged on opposite sides of said hollow member so as to communicate with said exhaust chamber; said two hollow horizontal insulators forming two horizontal chambers arranged coaxially to each other and symmetrical with respect to said hollow member; two stationary nozzle members arranged at the opposite sides of said hollow member and extending, respectively, into said two horizontal chambers and into said exhaust chamber; two contact members arranged, respectively, in said chambers movably from a first position into a second position, said movable contact members cooperating, respectively, in the first position thereof with said stationary nozzle members and being farther from each other in the second position thereof than in the first position and located in said two chambers; two current terminals connected, respectively, to said two movable contacts, one of said terminals leading current into the circuit breaker, the other of said terminals leading the current out of the circuit breaker; means for establishing an electrical connection between said movable contact members in the first position thereof said movable contact members being electrically disconnected when in the second position thereof; means including said hollow vertical support for introducing gas under pressure into said chambers; and means operated by the gas under pres-

sure when the pressure of the gas reaches a predetermined level, said gas operated means moving said movable contact members simultaneously from the first into the second position thereof; whereby the gas under pressure enters said exhaust chamber and the gap created by the movement of said contact members and extinguishes the arc formed therebetween.

15. A gas blast circuit breaker, comprising in combination, a hollow vertical support; a hollow member arranged on said hollow vertical support and having an exhaust chamber communicating therewith; two hollow horizontal insulators arranged on opposite sides of said hollow member so as to communicate with said exhaust chamber, said two hollow horizontal insulators forming two horizontal chambers arranged coaxially to each other and symmetrical with respect to said hollow member; two stationary contact members arranged at the opposite sides of said hollow member and extending, respectively, into said two horizontal chambers and into said exhaust chamber; two contact members arranged, respectively, in said chambers movably from a first position into a second position, said movable contact members cooperating, respectively, in the first position thereof with said stationary contact members and being farther from each other in the second position thereof than in the first position and located in said two chambers; two current terminals connected, respectively, to said two movable contacts, one of said terminals leading current into the circuit breaker, the other of said terminals leading the current out of the circuit breaker; means for establishing an electrical connection between said stationary contact members so as to connect said movable contact members electrically with each other in the first position thereof, said movable contact members being electrically disconnected when in the second position thereof; means including said hollow vertical support for introducing gas under pressure into said chambers; and means operated by the gas under pressure when the pressure of the gas reaches a predetermined level, said gas operated means moving said movable contact members simultaneously from the first into the second position thereof, whereby the gas under pressure enters said exhaust chamber and the gap created by the movement of said contact members and extinguishes the arc formed therebetween.
